Primary Examiner — Robert M Spear*Assistant Examiner* — Rhea Shields(74) *Attorney, Agent, or Firm* — Ward and Smith, P.A.(57) **CLAIM**

The ornamental design for a windowed closeable carton, as shown and described.

DESCRIPTION

FIG. 1 is a perspective view of a windowed closeable carton showing a new design;

FIG. 2 is a right side elevation view thereof, the left side being a mirror image;

FIG. 3 is a front elevation view thereof;

FIG. 4 is a rear elevation view thereof;

FIG. 5 is a top plan view thereof;

FIG. 6 is a bottom plan view thereof;

FIG. 7 is a cross-section view taken on line 7-7 of FIG. 5;

FIG. 8 is a cross-section view taken on line 8-8 of FIG. 5;

FIG. 9 is another perspective view thereof, showing the windowed closeable carton in an alternate open configuration; and,

FIG. 10 is another top plan view thereof, showing the windowed closeable carton in an alternate blank configuration.

1 Claim, 8 Drawing Sheets(56)
